ASSO. ATTORNEY.

UNITED STATES PATENT OFFICE.

FRANK M. ASHLEY, OF HAWTHORNE, ASSIGNOR OF ONE-FOURTH TO WOOD
McKEE, OF PATERSON, NEW JERSEY.

PROJECTILE.

SPECIFICATION forming part of Letters Patent No. 517,560, dated April 3, 1894.

Application filed February 29, 1892. Serial No. 423,109. (No model.)

To all whom it may concern:

Be it known that I, FRANK M. ASHLEY, a citizen of the United States, residing in Hawthorne, in the county of Passaic and State of New Jersey, have invented certain new and useful Improvements in Projectiles, of which the following is a specification:

This invention relates to a projectile constructed with an axial passage extending entirely through it and closed at its rear end by a cap loosely fitted thereto, so as to be thrown off by the force of the air passing through the projectile, after the latter is discharged, whereby the projectile will travel with less resistance, greater speed and distance, and in a straight course.

The invention has for its object to provide an improved projectile of this character, as hereinafter described and claimed.

20 The invention consists of the construction hereinafter described and claimed.

In the accompanying drawings: Figure 1 is a longitudinal section of the projectile comprehending my invention. Fig. 2 is an exterior view of the same projectile, and Fig. 3 is a detail.

30 The projectile is provided with an axial passage extending entirely through it. The object of this passage is to enable me to make the heaviest possible projectile of a given length which will meet with the smallest resistance of the air. A further object of the passage is to direct the flight of the projectile. When the projectile is inserted into the gun 35 for firing the rear end which receives the force of the explosion is covered with a cap, which is loosely applied to the projectile and is sufficiently strong to withstand the force of the explosion. When the projectile leaves the gun the pressure of the air through the axial 40 passage forces the cap off from the end of the projectile and thus provides an uninterrupted passage for the air, which materially reduces the resistance thereof.

Referring to the drawings by letter, *a* represents the body of the projectile, *b* represents the axial passage through it and *c* represents the cap over the rear end of the projectile.

45 In order to secure additional accuracy in the flight of a projectile and to dispense with the rifling of the gun barrel, I propose to make the forward end of the passage bell-shaped and to form spiral ribs *b'* thereon. When the air rushing through the axial passage during the flight of the projectile, strikes these spiral formations it will cause the projectile to rotate on its axis and thereby insure a straight course.

50 In Fig. 1 the passage *b* is shown lined with a tube *d* which has a cutting edge and flange projecting from the forward end to strengthen the projectile when the body is made of softer material, such as lead, and also to enable the projectile to pierce refractory substances 55 against which it is directed. This lining may be provided with the ribs or grooves as shown in Fig. 3, to impart the rotary movement to the projectile.

60 Having thus described my invention, I claim—

1. A cylindrical projectile having an axial passage extending entirely through it, an open ended tube fitting said passage and having a bell-shaped rifled mouth at its forward end. 75

2. A cylindrical projectile having an axial passage extending entirely through it and made of soft material, such as lead, and a lining tube of harder material than the body of the projectile and having its forward end reinforced for the purpose described.

80 In witness whereof I have hereunto signed my name in the presence of two subscribing witnesses.

FRANK M. ASHLEY.
